US00D987298S

(12) **United States Design Patent** (10) Patent No.: **US D987,298 S**
Xi et al. (45) Date of Patent: **** May 30, 2023**

(54) **ORAL CARE IMPLEMENT**(71) Applicant: **Colgate-Palmolive Company**, New York, NY (US)(72) Inventors: **Wen Jin Xi**, Shanghai (CN); **Robert Moskovich**, Manakin-Sabot, VA (US); **Guang Sheng Guo**, Yangzhou (CN); **Stephen Nelson**, New Brunswick, NJ (US); **Joachim Storz**, Zell am See (AT); **Felix Mueller**, Zell am See (AT)(73) Assignee: **Colgate-Palmolive Company**, New York, NY (US)(***) Term: **15 Years**(21) Appl. No.: **29/734,649**(22) Filed: **May 14, 2020****Related U.S. Application Data**

(60) Division of application No. 29/673,406, filed on Dec. 14, 2018, now Pat. No. Des. 887,144, which is a continuation of application No. 29/586,629, filed on Dec. 6, 2016, now Pat. No. Des. 840,691, which is a division of application No. 29/533,922, filed on Jul. 23, 2015, now Pat. No. Des. 777,446.

Primary Examiner — Steven J Czyz

CLAIM

The ornamental design for an oral care implement, as shown and described.

DESCRIPTION

FIG. 1 is a front perspective view of an oral care implement according to the new design;

FIG. 2 is a rear left perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.
